UNITED STATES PATENT OFFICE.

GEORGE A. WOODMAN, OF CHICAGO, ILLINOIS, ASSIGNOR TO KIRBY EQUIPMENT COMPANY, OF CHICAGO, ILLINOIS, A CORPORATION OF ILLINOIS.

JOURNAL-BOX LID.

1,076,853.

Specification of Letters Patent.

Patented Oct. 28, 1913.

Application filed April 22, 1912. Serial No. 692,351.

To all whom it may concern:

Be it known that I, GEORGE A. WOODMAN, a citizen of the United States, residing at Chicago, in the county of Cook and State 5 of Illinois, have invented certain new and useful Improvements in Journal-Box Lids, as set forth in the following specification.

My invention relates to journal box lids of that class which are particularly adapted 10 for use on railway car journal boxes.

One of the principal objects of the invention is to provide a dust-proof lid for journal boxes which will be simple in construction, cheap to manufacture and serviceable 15 in operation.

A further object of the invention is to provide a lid with means of simple construction for automatically and yieldingly holding the lid in open and closed positions and 20 so construct and arrange the parts of this means that they may be readily assembled and secured in place without the use of bolts, rivets or other permanent fastening devices.

Other objects and advantages of my in- 25 vention will be apparent as it is better understood from the following description which, taken in connection with the accompanying drawing, discloses one preferred embodiment thereof.

On the drawing—Figure 1 is a fragmentary vertical sectional view of a journal box provided with a lid made in pursuance of my invention; Fig. 2 is an enlarged vertical sectional view similar to Fig. 1 showing the 35 internal construction of the follower; Fig. 3 is a sectional view on the line 3—3 of Fig. 1; Fig. 4 is an enlarged front elevation of the follower shown in Figs. 1, 2 and 3, and Fig. 5 is a partial vertical sectional view 40 illustrating a modified form of the lug and follower.

For the purpose of illustrating my invention I have shown a journal box 10 which may be of any preferred form or construction having the opening 11 in its outer end and the lug 12 upon its upper wall 13. Through an aperture in the lug is positioned a pintle 14 upon which the lid 15 is pivotally mounted. The lug 12 is provided intermediate its ends with the upper inclined bearing face 17 and the front vertically disposed face 18 terminating in a shoulder 19 formed by providing a transversely extending groove or recess 20 in the front face of the lug. The two bearing faces 17 and 18

are connected together by the rounded edge 21. A follower or block 22 having a bearing face 23 adapted to engage the bearing faces 17 and 18 and a shoulder 24 shaped to engage the shoulder 19 and the rounded edge 21 is located within a housing 25 formed upon the lid 15. This housing is elevated above the front surface of the lid 15 and inclined thereto, a portion of the front wall of the lid being inclined outwardly as at 26 to 60 form the bottom of the said housing, the extremity of said outwardly inclined portion being connected to the main part of the front wall of the lid by means of the wall 27 formed integrally with the extremity of 65 the portion 26 and the main part of the wall. The housing 25 is preferably cast in a single piece with the lid and is so located with respect to the pivotal connection between the lid and lug upon the journal box that the 70 open end of the housing is opposed to the bearing faces of the lug. The follower 22 positioned within the housing is normally urged against the lug by a coiled expansion spring 28 interposed between the follower 80 and the front wall of the housing, the follower 22 being provided with a longitudinally extending cylindrical projection 29 fitting within the end of the coiled spring 28. To support the follower in proper position 85 I provide upon each side of the housing and extending inwardly thereof the flanges or shelves 31, each of which is preferably reinforced by a web 32 and upon opposite sides of the follower are formed lugs 33 adapted 90 to rest upon these flanges 31.

For the purpose of lubricating the bearing surfaces to facilitate the opening and closing movements of the lid the follower is provided with a core or recess 34 adapted 95 to receive a lubricating agent such as heavy grease or waste saturated with a lubricating oil which is inserted in the core before the device is assembled. An aperture 35 communicating with the core 34 permits the 100 lubricant to be distributed over the bearing faces 17, 18 and 23 of the lug and follower respectively.

In the modified form of my invention shown in Fig. 5 the housing 41 and the 105 spring 42 are substantially identical with the housing 25 and spring 28 described in connection with Figs. 1, 2 and 3. The front wall of the lug 44 however is undercut 110 to provide the shoulder 45, and the bearing

face of the follower 46 which is formed substantially flat is provided at its upper end with the shoulder 47. When the lid is in closed position, as shown in Fig. 5, the shoulder 47 rests under and abuts against the shoulder 45 of the lug, holding the lid in closed position and preventing flapping and jiggling of the lid in service. When the cover is opened the shoulder 47 is forced inwardly of the housing 41 against the force of the spring 42 by the shoulder 45 and the shoulder 48 formed at the lower edge of the follower moves up and yieldingly engages the shoulder 45 to retain the lid in open position.

It will be manifest that a lid equipped with a spring pressed follower in accordance with my invention will yieldingly retain the lid in both open and closed position, the resistance to movement of the lid afforded by the construction disclosed being dependent of course upon the force of the spring actuating the follower.

It will be manifest also that various changes may be made in the form and construction of the parts and arrangements without departing from the spirit and scope of my invention, or sacrificing any of its advantages, the form hereinbefore disclosed being merely one preferred embodiment thereof.

I claim:

1. The combination of a journal box provided with a lug having a flat face on its forward side and provided with a shoulder at its upper edge extending beyond said flat face and provided also with a shoulder at its bottom located inwardly of said flat face, a lid pivotally connected to said lug, a follower carried by said lid and having a flat forward face terminating in a forwardly extending shoulder at its bottom and a rounded shoulder at its top, the faces and shoulders of the follower and lug being so arranged that the lower shoulder of the follower engages the inwardly disposed shoulder at the bottom of the lug and the rounded shoulder at the top of the follower engages beneath the outwardly extending shoulder of the lug when the lid is in closed position and the lower shoulder of the follower engages the outwardly extending shoulder of the lug when the lid is in open position and means yieldingly pressing said follower against the lug.

2. The combination of a journal box provided with a lug having a flat face terminating in shoulders at its upper and lower edges, a follower carried by the lid and having a flat face adapted to contact with the

said flat face of the lug and terminating in a shoulder at its lower edge adapted to engage the said shoulders of the lug, said flat faces and shoulders of the lug and follower being arranged to permit the flat face and lower shoulder of the lug to contact with the flat face and shoulder of the lid when the latter is in closed position and permit the upper shoulder of the lug and the shoulder of the lid to engage when the latter is in open position, and means for yieldingly pressing said follower against said lug.

3. The combination of a journal box having a lug formed thereon, a lid pivotally connected to said lug, and provided with an open ended housing having inwardly extending shelves, a follower positioned in said housing, and having outwardly extending lugs adapted to rest upon the said shelves to support the said follower, and a spring normally pressing the said follower against the said bearing lug whereby the lid is retained in open and closed position.

4. The combination of a journal box having a lug formed thereon, said lug being provided with a plurality of bearing faces, a lid pivotally connected to said lug, a follower slidably mounted in said lid and provided with a bearing face adapted to engage the bearing faces of the lug, and a spring normally pressing the said follower against the said lug, said follower being provided with a recess adapted to contain a lubricant, and having an aperture through which the lubricant is supplied to the coöperating faces of the lug and follower.

5. The combination of a journal box having a lug formed thereon, a lid pivotally connected to said lug and provided with an open-ended housing, a follower positioned in said housing, means extending inwardly of the housing and engaging the said follower for supporting the follower and guiding it longitudinally of the housing, and means for pressing said follower against the lug.

6. The combination of a journal box having a lug formed thereon, a lid pivotally connected to said lug and provided with an open-ended housing, a follower positioned in said housing and provided with oppositely extending supporting lugs engaging said housing for supporting and guiding said follower longitudinally of the housing, and means for pressing said follower against said lug.

GEORGE A. WOODMAN.
